J. W. LEWIS.
UMBRELLA.
APPLICATION FILED JUNE 26, 1911.

1,081,126.

Patented Dec. 9, 1913.

UNITED STATES PATENT OFFICE.

JOHN W. LEWIS, OF SAN FRANCISCO, CALIFORNIA.

UMBRELLA.

1,081,126.

Specification of Letters Patent.

Patented Dec. 9, 1913.

Application filed June 26, 1911. Serial No. 635,267.

To all whom it may concern:

Be it known that I, JOHN W. LEWIS, a citizen of the United States, and a resident of San Francisco, in the county of San Francisco and State of California, have made certain new and useful Improvements in Umbrellas, of which the following is a specification.

My invention is an improvement in umbrellas, and has for its object the provision of a simple and efficient means for detachably connecting the ribs and braces to the stick and runner respectively, wherein each connection is independent of the other connections.

In the drawings—Figure 1 is a vertical section of a portion of the frame, Fig. 2 is a front view of the notch, Fig. 3 is a front view of the cap, Fig. 4 is a bottom plan view 20 of the notch and cap, Fig. 5 is a plan view of a modified form of rib. Fig. 6 is a plan view of a portion of the cover, and Fig. 7 is a vertical section of a modified form of cap on the ordinary runner.

25 In the embodiment of the invention shown in Fig. 1, the stick 1 is of ordinary construction, and the notch is in the form of a ferrule or sleeve 2, having a depending annular flange 3 connected to the ferrule or sleeve by a flaring or tapering portion 4. The flange 3 is provided at spaced intervals with notches or slots 5, for receiving the ribs 6, and each of the ribs 6 is provided at its inner end with a transverse integral 30 cross head 7 as shown in Fig. 5 or with a transverse pin 8 as shown in Fig. 1.

35 The notch, as shown in Fig. 2 is provided with an annular groove or channel 9, in its outer face, intermediate the end of the notches 5, for receiving the pin 8 or cross head 7, and the cap which comprises a ferrule or sleeve 10 and a depending annular flange 11 of greater diameter than the ferrule, connected to the ferrule by a flaring or 40 tapering portion 12, fits over the notch, and over the ends of the ribs. The said flange 11 of the cap is provided with spaced substantially parallel notches or slots 13, which register with the slots 5, when the cap is in 45 place on the notch, and permit the free vertical swinging movement of the ribs, in raising and lowering the umbrella or parasol.

Both cap and notch are fixed in place on the stick by means of a pin 14, passed 50 through cap, notch and stick, and headed or upset at each end. The pin 8 or cross head

7 is received in the groove 9, of the notch and hinges the rib to the stick.

The method of connecting the inner ends of the braces or struts to the runner 60 resembles very closely the method of connecting the inner end of the rib to the stick. Each brace 21 is provided at its inner end with an integral cross head like that shown for the rib in Fig. 5 or with a transverse 65 pin 24, as shown in Fig. 1. The runner is in the form of a sleeve 15, encircling the stick and slideable thereon, and at its upper end the sleeve is provided with a flaring flange 17, having spaced substantially parallel notches or slots 20 for receiving the braces, and with an annular groove 22 similar to the groove 9 for receiving the pin or cross head. The inner end of the brace is precisely like the inner end of the rib, and 70 the sleeve corresponds closely in structure 75 to the structure of the notch. A cap 28 is fitted over the flange 17 and is provided with notches or slots 27 registering with the slots 20 of the flange 17, when the cap is in 80 place. The notch is provided with an external thread at its small end with which 85 engages a threaded nut 30 on the runner, and is also provided with an external annular rib 31. The flange 17 may be integral 90 with the runner or detachable, and the groove 22 of the said flange receives the cross head or pin of the strut in the same manner that the groove 9 receives the corresponding portions of the ribs.

95 Each strut 21 is pivoted to a rib intermediate the ends of the rib, as indicated at 32, and the cover 33 is fitted on the ribs in the usual manner. The outer edge of the cover may be connected to the outer ends of the ribs and to the stick by means of the detachable tips and the ring forming the subject matter of my copending application Serial No. 575,234 filed August 3, 1910.

100 Intermediate its ends, each rib is connected to the cover by the means shown in Fig. 6. The said means comprises tapes or straps 34 secured to the cover at suitable points adjacent to the ribs and transversely thereof. The central portion of the strap is free 105 from the cover, and the rib is provided with oppositely arranged hooks 35 for engaging the strap. Each hook is connected at one end to the rib, and the other end is pointed at 36, and is bent toward the rib and then 110 away therefrom, to permit accidental disengagement of the hooks from the strap.

The runner is provided with the usual slot 37 for engagement by the usual spring latch (not shown) to hold the cover extended or folded. The weak point in the ordinary 5 umbrella or parasol is the wire holding the rib and braces to the notch or runner. The said wire soon becomes rusty and breaks releasing every rib or brace as the case may be.

In the present construction should a pin 10 or cross head become broken, but one rib or brace is released, the remainder holding firmly in place, and the rib or brace may be easily replaced, by removing the cap. The frame is assembled by engaging the ribs 15 with the notch, placing the cap over the notch, and securing both in place by the pin. The braces are then connected to the ferrule of the runner, and the runner cap is screwed down on the ferrule. The cover 20 may then be placed. The transverse pin being spaced from the inner end of the rib or brace, presents a somewhat stronger construction than the cross head, and for this reason is preferable for heavy work, while 25 the cross head is more adapted for light work, such as parasols.

The improved construction is not liable to get out of order on account of wet, since 30 the cap incloses the connection and prevents the entrance of any great amount of moisture.

In Fig. 7 the upper end of the runner shows a modified form of cap. The said cap 40 is provided with resilient arms 41 35 each having a catch 42 at its free end for engaging above the flange 17 of the runner. The above construction is especially adapted for light service. The upper portion of the runner just mentioned is in fact a notch 40 closely resembling that shown in Fig. 3 and

the notch is held on the runner by means of a bead 43 on the runner near its upper end, and a lateral flange 22 at the upper end, the notch being held between the bead and flange.

45

I claim:

1. In an umbrella frame, a connector comprising a pair of substantially frusto-conical sleeves fitting one within the other, the outer sleeve having at its large end resilient 50 catches engaging the adjacent end of the inner sleeve for preventing disengagement of the said sleeves, said sleeves having laterally spaced notches extending from the large end toward the small end, and the 55 inner sleeve having an external annular groove intersecting the notches intermediate their ends, the said sleeves being adapted to engage a stick, and ribs and stretchers engaging the notches at one end and having 60 lateral lugs for engaging the groove of the inner sleeve.

2. In an umbrella frame, a connector comprising a pair of substantially frusto-conical sleeves fitting one within the other, said 65 sleeves having laterally spaced notches extending from the large end toward the small end, and the inner sleeve having an external annular groove intersecting the notches intermediate their ends, the said sleeves being 70 adapted to engage a stick, and ribs and stretchers engaging the notches at one end and having lateral lugs for engaging the groove of the inner sleeve, and means for detachably connecting the sleeves.

JOHN W. LEWIS.
